BACKLASH ELIMINATOR

Erwin G. Roehm and Walter D. Archea, Norwood,
Ohio, assignors to The Cincinnati Milling Ma-
chine Company, Cincinnati, Ohio, a corpora-
tion of Ohio

Application October 20, 1933, Serial No. 694,423

12 Claims. (Cl. 90—22)

The present invention relates to improvements in machine tools embodying a movable table or other support such as milling machines, and has for an object the provision in connection with such machines having feed and quick traverse of the table or movable support thereof in either direction, of a back lash eliminator which is only operative and effective during the feeding movement of the table and which is ineffective during quick traverse movement.

Another object of the invention is to provide an efficient back lash eliminator for a moving support, wherein the back lash eliminator is equally effective when said support is moved at feed rate in either direction, and wherein the production of back lash elimination tendency is higher when the feed resistance is light, and the tendency to vibration and chattering of the support is great, and conversely, wherein the resistance effect of the back lash eliminator automatically decreases under conditions of higher feed resistance when vibration and chatter of the support is reduced because of the very nature of the cut.

A further object of the invention is to provide in a machine tool, hydraulically controlled means for manually and automatically effecting desired cycles of support operation including feed and quick traverse movements in either direction and stops, and cooperating back lash eliminating mechanism hydraulically and automatically rendered operative during feed rate movement only of the support or table.

An additional object of the present invention is the provision of a mechanism which will impose a restraint on movement of a machine tool support when being driven at a feed rate, and/or when the feeding impulsion is disconnected therefrom whereby maximum accuracy of stopping or reversing of the support is insured and tendency to over-run due either to inertia or cutter action counteracted.

These and other objects are attained by the means described herein and disclosed in the accompanying drawings in which:

Figure 1 is a perspective view of a milling machine having the mechanism of the invention embodied therein.

Figure 2 is a schematic hydraulic circuit dia-
gram embodying the several automatic controls for the machine shown in Figure 1.

Figure 3 is a plan view showing the back lash eliminator mechanism of the invention as applied to a rotating nut feed for a sliding work support-
ing table.

Figure 4 is a plan view of a rack and pinion type of feed drive embodying the back lash eliminator of the invention.

Figure 5 is a plan view showing a worm and worm gear type of drive embodying the means of the invention.

Figure 6 is a schematic view showing the power source and mechanical controls governing the direction of feed of the work supporting table, the table feed clutch, and rapid traverse drive for the machine shown in Figure 1.

In milling machines wherein the material acted upon is carried by a movable table or work support to a rotary cutter, it is desirable for production purposes to control both table movement and cutter operation by automatic as well as by manual control means. Furthermore, in cutting operations where the direction of effective movement of the engaging teeth of the cutter and the direction of relative feed of the work and cutter is the same, and also in face milling operations wherein the surface of the work operated upon is unequally distributed in parts relative to the cutter, it is necessary to overcome the back lash or tendency to lost motion between the support and the actuating means therefor. This so-called back lash causes chattering and vibration of the support and results in inaccurate and/or "tooth-marked" work if not properly eliminated, and jumping of the support as the hook-in cut becomes effective.

The milling machine of the present invention is adapted to accurate and speedy production operations of all kinds and to this end embodies a combined automatic hydraulic and selective manual control for the feed and quick traverse movements of the table in either direction and automatically and hydraulically controlled back lash eliminator mechanism effective to the necessary and proper degree according to the feed resistance to the movement of the table.

Figure 1 shows a milling machine equipped with hydraulically operated automatic controls and embodying the back lash eliminator of the invention.

The machine consists essentially of a base 12, column 13, having an overhanging arm 14 which supports the free end of the cutter arbor 15. A feed screw 16 cooperating with power driven nuts 17 and 18, (Figure 3) serves to effect longitudinal movement in either direction of a sliding work supporting table 19. A bracket housing 20 at the front of the machine houses the hydraulic valve mechanism and the combined manual and automatic control means therefor. Control lever

21 projects from housing 20 and is the means whereby the manual control of the machine is effected. An auxiliary dog rail 22 is adjustably and removably attached to the work support table 19 and carries adjustable dogs for cooperation with trip plungers extending from the rear of housing 20.

Referring now to Figure 3 a pair of bearing bosses 23 and 24 integral with bed 12 are provided with thrust bearings 25 against which the feed nuts 17 and 18 abut and through which the co-operating feed screw 16 extends.

The back lash eliminator mechanism is interposed in the table feed transmission just ahead 15 of the table feed device as will later be fully explained.

In order to simplify the explanation of the machine embodying the invention the feed and quick 20 traverse transmissions for the table will be described first in connection with the schematic view in Figure 6.

As shown in Figure 6, the power from a suitable source, such as motor 26, serves to operate the main feed drive shaft 27 through rotatable 25 members 28 and drive band 29. The main drive shaft has a feed clutch 30 controlling the transmission of power through suitable gearing 31 and pick-off gears 60 and 62 to a final drive shaft 32. The shaft 32 drives shaft 33 through a suitable 30 reversing clutch 34 which may be alternately engaged to transmit clockwise or counter-clockwise rotation to shaft 33. An overrunning clutch 35 on shaft 32 and a gear 36 on the same shaft and cooperating with a clutch controlled rapid traverse drive gear 37 on shaft 27 together with a feed brake 131 complete the mechanical transmission controls of the machine. A rapid traverse clutch 41 serves to connect gear 37 to shaft 27.

40 In the above mentioned drawings, there are illustrated several characteristic embodiments of the back lash eliminator of the invention, and also the adaptation of one of them to the automatic type of milling machine, the latter adaptation being illustrative of the utility of the back lash eliminator in hydraulically controlled machines and of certain novel control means as well.

Referring to Figure 3, feed nut 17 has an integral or attached right hand helical gear 85 with 50 the teeth thereof inclined at an angle of the order of forty-four degrees (44°). The nut 18 has a left hand helical gear 84 integral therewith or fixed thereto and having the teeth thereof inclined at an angle of the order of thirty-two degrees (32°). Gear 88 has the same ratio in number of teeth to gear 84 as gear 88 has to gear 85. Gears 84 and 85 have an equal number of teeth. A spool 86 is splined on hollow shaft 87 and has fixed gears 88 and 89 on its opposite 60 ends matching the gears 85 and 84 respectively. The spool has a longitudinal slot 90 through which a pin 91 mounted on plunger 92 may operate under the influence of hydraulically controlled piston 93 to exert pressure axially of the spool. 65 Gear 94 is suitably keyed to shaft 87 and is driven by a gear 95 on shaft 96 which receives its power at suitable speed and direction of rotation through reverser shaft 33 of which shaft 96 is a continuation.

70 When the rapid traverse mechanism is operative as in shifting the work supporting table quickly and without cutting load, piston 93 is relieved of pressure and assumes a substantially central or neutral position as will spool 86. Since 75 the spool is thus free to float endwise, rotation of

gear 88 will be resisted by whatever load is on gear 85 and due to the spiral angle of the teeth, there will be a reaction tending to shift gear 88 to the left. This movement will cause relative axial movement of gear 89, which due to its 5 spiral being reversed to gear 88, will tend to cause opposite rotation of gear 84 which will form a reaction to further movement and balance the drive through the two branches.

In climb cutting operations, and in face milling operations wherein the surface of the work operated on is unequally distributed in parts relative to the cutter, the back lash or tendency to lost motion between feed screw 16 and the drive nuts 17 and 18 is overcome by exerting an axially 10 or longitudinally directed pressure on the spool 86 through the agency of hydraulic pressure exerted on piston 93 in chamber 91. Gears 88 and 89 having the teeth thereof at different degrees of angularity and of opposite direction of angularity 15 have unequal amounts of end thrust in opposed directions in their cooperative relation with their respective companion gears 85 and 84, respectively. By exerting the proper amount of pressure axially of the spool 86, and in a direction 20 opposing the greater directional end thrust of gear 88, the slight amount of clearance between the threads of the feed screw and the threads of the drive nuts 17 and 18 is taken up so that one nut bears against one side face of the threads and the 25 other nut against the opposite side face of the threads of the screw, and no back lash or lost motion exists. There is thus eliminated any 30 tendency to chattering of the machine or undesired movement of the controlled support. 35 When the direction of rotation of spool 86 and its gears is clockwise (viewing the gears from the right hand end of Figure 3), the greater end thrust of gear 88 is to the left hand side and the lesser end thrust of gear 89 is toward the right hand side. 40 Under such conditions the hydraulic pressure is imposed on the left hand face of piston 93 to oppose the end thrust due to the steeper angle of teeth on gear 88. If this pressure in cylinder 91 is just sufficient to overcome the tendency to 45 end movement of gear 88, or in other words sufficient to hold gear 88 into tight driving contact with 85, the nut 17 will be held advanced due to the angularity of the intermeshing spiral 50 teeth as far as possible, so that the nut 17 will be 55 in tight engagement with one angular side of the screw thread and so that any further rotation must cause axial movement of the screw. Due to this condition, the gear 89 being integral with gear 88, is also axially moved, but the angularity 60 of its teeth being reversed to that of gear 88, will cause reverse rotary movement of gear 84 to its limit of movement so that the nut 18 is 65 in tight engagement with the opposite side of the screw thread. It will now be seen that no back 70 lash exists, and an external force acting to cause movement of the table will be resisted by nut 18; but at the same time the nut 17 is maintained in a potential positive driving condition so that at any time the external force momentarily diminishes, or disappears entirely, the table will still be moved at the same rate without interruption. As a matter of fact only a certain range of hook-in cuts, such as up to a certain depth for instance, cause this acceleration tendency of the table over the desired feed rate. But 75 this acceleration tendency of the cutter is not steady and uniform but intermittent in nature, ranging from low pressures incapable of causing acceleration of the table to momentarily ex-

tremely high pressures. Therefore, by having one member in a driving position and the other member in a holding back position, a uniform feed is obtained. Should the depth of cut increase beyond this range due to unevenness of the work piece, the acceleration tendency of the cutter will not only reduce to zero but a great resistance to table movement might be created so that a load is thrown on the table drive. Should this load become so great, that the axial component of gear 88 is greater than the opposing hydraulic pressure, then the sleeve 86 will shift against the resistance of the hydraulic pressure causing gear 89 to rotatably accelerate gear 84 from a holding back or retarding position into an intermediate or neutral position, and finally into a driving position causing nut 18 to assist the nut 17 in feeding the table. Since the hydraulic pressure is still active, it will be seen that simultaneously with a decrease of table load, the sleeve 86 will shift again to move nut 18, through the medium of gears 84 and 89, to a back lash eliminating position. This important feature of the invention not only makes it possible for nut 18 to act as retarding means to eliminate back lash but also to act automatically whenever the necessity arises to assist in the actual driving of the table. When the direction of rotation of the spool 86 is reversed, for the purpose of feeding the table 19 in the opposite direction, the greater end thrust of gear 88 is toward the right and hydraulic pressure is applied to the right hand side of piston 93 to oppose this greater pressure to prevent locking of the parts. When rapid traverse drive of the work supporting table takes place, no hydraulic pressure is exerted on the piston and the spool gear and the reaction of the drive on the gears in the absence of cutting load tends to centralize 86 and cause relatively free movement of the support.

In the embodiment shown in Figure 3, which is the form used in the machine of Figure 1, the gears 85 and 84 are co-axial. In the modifications of Figures 4 and 5, it will be noted that the corresponding gears need not be co-axial, but that various arrangements may be had to accommodate the back lash eliminator to different types of mechanism.

The same general arrangement can be used with a rack and pinion drive, for example, as shown in Figure 4. The back lash eliminator in this embodiment may constitute spool gear 98 splined on shaft 99 which is at right angles to a rack 100. Shaft 99 is driven from shaft 101 through the agency of miter gears 102 and 103.

The spool gear is subject to longitudinal shifting by hydraulic pressure admitted to chamber 104 through suitably controlled pressure tubes 105 and 106 at opposite sides of piston 107. The piston rod 108 may have connection with the slideable spool 98 similar to that illustrated in Figure 3. The spool 98 has helical gears 109 and 110 at the opposite ends thereof, the gear 109 having its teeth at greater angularity than and in opposite direction to the teeth of gear 110. Gear 109 is a right hand gear with the teeth preferably disposed at an angle of about forty-four degrees (44°). Gear 110 is a left hand gear and has its teeth disposed at an angle of approximately thirty-two degrees (32°).

Gear 109 meshes with gear 111 on a suitable journaled shaft 112 that carries drive pinion 113 meshing with rack 100.

Gear 110 meshes with gear 114 on shaft 115 and carries drive pinion 116 meshing with rack

100. Shaft 99 in this embodiment is disposed intermediate and parallel to the spaced parallel shafts 112 and 115. When shaft 99 is rotated in clockwise direction the spool gear 98 turns gears 111 and 114 counter-clockwise and the pinions 5 113 and 116 turn with them for effecting relative movement of the rack and pinion. At such times as working conditions render elimination of back-lash desirable, as when cutting, hydraulic pressure is admitted through pressure tube 105 or 106 to oppose the greater end thrust of gear 109 sufficiently to restrict or limit the relative movement of the gears to an amount just sufficient to accomplish this adjustment of the pinions with respect to the rack teeth. 15

In Figure 5 there is shown the adaptation of the back lash eliminator of the invention to a worm and worm gear drive. In this embodiment the hydraulically controlled spool 117 has the gears 118 and 119 thereof arranged with the teeth in opposite and unequal angularity, for example as explained in connection with Figures 3 and 4. Gear 118 meshes with gear 120 on shaft 121 which carries worm 122 meshing with worm wheel 123. Gear 119 meshes with gear 124 on a shaft 125 which may be parallel but not necessarily aligned with shaft 121. A pair of miter gears 126 and 127 on the shafts 125 and 128, respectively, serve to effect rotation of worm 129 meshing with a second worm gear, located behind worm 123 and therefore not shown. Through the proper adjustment of hydraulic pressure through the device indicated generally at 130, the clearance between the threads of the respective worms 122 and 129, and their intermeshing worm gears 35 30 35 may be adjusted according to the direction of drive in a manner which will be well understood from the description of the backlash eliminator in connection with Figures 3 and 4.

Referring now to the machine shown in Figure 1 40 which employs the back lash eliminator mechanism illustrated in Figure 3, it will be explained in connection with Figure 2, how this eliminator may be interconnected and operated by the automatic hydraulic and selective manual control so 45 as to function in accordance with the different cycles.

It will be understood that the feed clutch 30, feed brake 131, rapid traverse clutch 41, directional reverse clutch 34 and back lash eliminator 50 control piston 93 are all hydraulically actuated through suitable pressure lines receiving oil from an oil sump or reservoir 132 through pump 40 and a main hydraulic pressure line 133. Valves controlling auxiliary pressure lines to the several instrumentalities are controlled manually through the lever 21; and associated trip plunger mechanisms are interconnected therewith and subject to automatic actuation by plungers operable by a group of control dogs mounted on the 55 adjustable dog rail 22.

The pressure supply line 133 has a connection 60 65 70 75 80 85 90 95 100 105 110 115 120 125 130 135 140 145 150 155 160 165 170 175 180 185 190 195 200 205 210 215 220 225 230 235 240 245 250 255 tively to rapid traverse, feed, and stop. The rapid traverse connection is through line 143, valve 144, and line 145 to the rapid traverse control 37. In the position shown the rapid traverse control is operative through line 143; while line 145 to feed brake 131, and also line 146 to feed clutch brake 300 are without pressure. Feed clutch 30 is of the spring opened and hydraulically closed type. In the position shown, the 10 valve piston 301 is under the influence of its spring by reason of no pressure in line 146 which communicates with the opposite end of the piston. A branch line 302 of line 133 at this time directs its pressure through line 303 to urge feed clutch 15 30 to engaged position. A by-pass 304 to the sump is closed at this time. Further, the piston 93 of the back lash eliminator in chamber 97 is not under pressure because line 147 is connected through by-pass 148 to sump connection 20 149 and line 150 from the opposite end of chamber 97 is connected through by-pass 151 and line 152 through resistance 153 to sump connection 154. Valve 155 has connections at its opposite ends through lines 156 and 157 with lines 146 25 and 137, respectively. Thus valve 155 is always conditioned in accordance with the direction valve 135 and with the direction clutch control piston 138 to direct the pressures from line 152 to the proper end of cylinder 97 to cause the 30 back lash eliminator to act automatically in the correct direction in accordance with the direction of feed. An automatic spindle stop mechanism may also be provided to act in proper coordination with the back lash eliminator whereby the 35 spindle will be automatically stopped when the back lash eliminator is off as when the table is moving at rapid traverse; and rotating when the back lash eliminator is on as when the table is connected to the feed mechanism. An electric 40 limit switch 305 is provided for starting and stopping the spindle actuating motor. This switch is moved to its stop position, shown in Figure 2, by an hydraulic actuated piston 307 through intervening lever 306. Fluid pressure is supplied 45 through line 308 for shifting piston 307 to the left, this line being connected through cannelure 309 in valve 310 to rapid traverse supply 143. The fluid acting on the other end of piston 307 is exhausted through bore 311, adjustable valve 50 312, and line 313 which is connected at this time by cannelure 314 in valve 310 to line 145 in turn connected to exhaust at this time as previously explained. Pressure is applied to line 152 when valve 142 is shifted upwardly to its feed position 55 to close the rapid traverse supply line 143 and connect the pressure supply branch 158 of the main line through port 159, line 145, through branch line 160, pressure reducer 161 and thence through 152 connected to the pressure reducer 161. The amount of pressure drop may be varied 60 by manually adjusted cam 325 acting to vary compression of spring 326 which is opposed by the pressure acting on the upper end of the valve plunger. If valve 155 is positioned, as 65 shown, with the line 152 communicating with valve groove 151, then pressure is directed through line 150 to the left-hand end of chamber 97, the opposite end at this time exhausting through line 147, by-pass 148, to sump connection 149. If 70 the direction valve 135 is shifted, then the pressure would be in the reverse direction, in chamber 97, entering through line 152, passage 148 and line 147 to the right hand end of chamber 97 and exhaust would pass from the left hand 75 end of the chamber 97 through line 150, by-pass

151, and sump connection 162. It will now be seen that the backlash eliminator piston is automatically subjected to pressures whenever the feed clutch is engaged and the rapid traverse clutch disengaged. Furthermore, it will be noted 5 that since line 143 is now a return and line 145 a pressure chamber, flow through lines 308 and 313 will be reversed, the pressure fluid entering line 313 forcing wide open the needle valve to provide free flow to bore 311, thereby shifting 10 plunger 307 to the right and actuating switch 305 to start the spindle motor.

When valve 142 is again shifted upwardly to its third or stop position, the continuation 163 of branch main 158 opens up pressure communication 15 through port 164 to line 146, while still maintaining pressure connection to line 145 but connecting line 143 to reservoir.

The pressure in line 146 moves a valve piston 301 against its spring to close line 302 and at 20 the same time connect line 303 with by-pass return 306 to release clutch 30 under the influence of its spring. The feed clutch brake 300 operates at this time to avoid overrunning of the table movement. It will thus be seen that although 25 pressure is still on in line 145 which normally would cause the spindle to rotate, pressure in line 146 reverses the connection in such a manner that the spindle is stopped. Also it should be noted that when valve 142 is shifted from its 30 rapid traverse position to its stop position without a stop at the feed position, that although the backlash eliminator is off or ineffective during rapid traverse, it becomes effective when the table is stopped. This insures against lost motion 35 should the table be manually adjusted as for set-up purposes and that the table will be accurately positioned. Means have been provided whereby the operator may selectively determine for himself when the backlash eliminator is on or is not 40 effective. In the construction thus far described, the backlash eliminator is always effective during feed regardless of direction. In cases it may only be desired when feeding in one direction such as feeding to the left only, or feeding to the 45 right only; or it may not be desired at all. These various adjustments are effected by a rotatable valve 315 having a pair of arcuate shaped grooves 316 and 317 of sufficient length when the valve is in a central position to connect lines 147 and 50 146 to branches 318 and 319 communicating with selector valve 320 which has two plungers 321 and 322, reciprocably mounted therein for movement against a spring 323. Thus when pressure is on line 137, pressure in line 318 will act on 55 the end of plunger 321 to move plunger 322 to effect inter-connection between lines 160 and 145. Likewise, when pressure is on line 136 due to change in direction of table movement, pressure in branch 319 will act on the end of plunger 322 60 to lift the same and interconnect line 160 with 145. Thus, the back-lash eliminator is effective in both directions of feed and in the manner previously explained. Clockwise rotation of valve 315 a predetermined amount will maintain connection between line 137 and branch 318, but will disconnect branch 319 from line 316 and connect it to return line 324, thus making the back-lash eliminator effective only in the direction of feed determined by line 137.

Clockwise rotation of valve 315 the same amount will reverse the connections so that back-lash eliminator is only effective during the direction of feed determined by line 136.

If the valve 315 is rotated still further beyond 75

the positions described, both branches 318 and 319 are disconnected from their respective central lines 316 and 317 and the back-lash eliminator is not effective at all.

5. The valves 135, 141 and 142 may be operated by means of the following mechanism:

An oscillatable and longitudinally reciprocable sleeve 169 is provided for actuation by the manually operable lever 21. This sleeve is connected 10 by means of the double bell crank 183 to plungers 135 and 141, and in such a manner that when the valve 135 moves in one direction the valve plunger 141 moves in an opposite direction. Rotary oscillation of sleeve 169 actuates through the 15 pivoted lever 191 the control valve plunger 142.

Besides being manually operated by the lever 21, the sleeve 169 may be automatically actuated by the axially movable and rotatable trip plunger 188. An auxiliary stop plunger 196 may be provided in addition to the trip plunger 188 for automatically shifting the same to a stop position. This plunger may be provided with a pawl 197 pivotedly mounted within a slot formed in the plunger and urged outward by a spring pressed 25 pin 198. The end of this pawl is thus held in the path of a shoulder 200 of a pivoted arm 201 which carries near its free end a lug 202 which engages in a groove 203 formed in plunger 188. Since the 20 form of the automatic trip mechanism for actuating these valves forms no part of the present invention, further description thereof is not believed to be necessary.

There has thus been provided an improved mechanism for eliminating backlash from a machine tool transmission and which may be selectively rendered operative or inoperative and either automatically or manually in accordance with the cycle of operation of the machine.

What is claimed is:

40 1. In combination with a hydraulically controlled machine tool having a movable work feed table and hydraulically controlled power means for effecting selected movements of said table at selected speeds in opposite directions, of back-lash 45 eliminator mechanism operative on the table moving means at certain speeds and comprising constantly engaging drive means including a pair of driving helical gears of opposite and unequal tooth angularity rotating as a unit, hydraulically means to exert axially directed pressure to shift 50 said unit and a pair of independent helical gears meshing respectively with the gears of said unit and driven at uniform speed thereby, the longitudinal shifting of the unit effecting a limited differential 55 rotational adjustment of said independent gears, independent feed means operable respectively by said independent helical gears and a feed element engaging with said pair of independent feed means.

60 2. In combination with a pair of relatively movable members, of a pair of rotary feed elements on one of said members, a complementary feed element on the other of said members engaging with said pair of feed elements and back-lash 65 eliminating mechanism whereby one of said pair of feed elements may be retained in advanced engaging relation to the complementary feed element to oppose back lash between said relatively movable members, and comprising a pair of helical 70 gears of opposite and unequal tooth angularity attached respectively to said pair of feed elements, an axially shiftable driving member having gear teeth complementary to those of said pair of helical gears and meshing therewith, means to selectively rotate the driving member

in opposite directions and means to apply pressure axially of the shiftable driving member to limit the advanced engaging relation of the said feed element.

3. In combination a pair of relatively movable members, feed means to effect movement of one of the members relative to the other, and comprising a single feed element on one member and a pair of feed elements on the other member engaging the feed element on the first mentioned 10 member; and anti-back lash mechanism comprising helical gears of opposite and unequal tooth inclination respectively on said pair of feed elements, a longitudinally shiftable power actuated rotary spool having at its opposite ends teeth 15 meshing respectively with the teeth of said helical gears and means to exert an axially directed pressure to said spool.

4. The combination with a pair of relatively movable members, of a feed mechanism for effecting relative movement between said members and comprising a pair of rotary driven elements carried by one of the members and a member on the other movable member cooperating with said pair of rotary elements, a rotating and longitudinally shiftable spool, gear teeth at opposite 20 ends of the spool, the teeth at one end being inclined in one direction, the teeth at the opposite end being oppositely inclined and at a different angle of inclination from the first mentioned 25 teeth, companion gears meshing with the teeth at opposite ends of the spool, said gears effecting movement of the respective driven rotary elements, and means to exert axially directed pressure on the spool against the thrust of the meshing 30 gears of greater teeth angularity.

5. The combination with a pair of relatively movable members, of a feed mechanism for effecting relative movement between said members and comprising a pair of rotary driven elements 40 carried by one of said members and a member on the other of said members cooperating with said pair of rotary elements, a spool member shiftable longitudinally and rotatable in opposite directions, gear teeth at opposite ends of the 45 spool, the teeth at one end being inclined in one direction, the teeth at the opposite end being oppositely inclined and disposed at a greater angle to the spool than the first mentioned teeth, companion gears in driving relation with the respective rotary driven elements and with the respective teeth at opposite ends of the spool, the respective series of teeth at opposite ends of the spool and their respective companion gears exerting unequal end thrust pressure in opposite 55 directions, and means to exert axial pressure on the spool in opposition to the greater end thrust of the gears.

6. In a back lash eliminator the combination with a pair of rotary driven elements, a cooperating element engaging both said rotary driven elements, means to drive the rotary driven elements at uniform speed, said means including gears for the respective rotary driven elements and having oppositely and unequally inclined teeth and 60 a spool member meshing at its opposite ends with the respective gears provided with a means to exert axial pressure on said spool whereby a predetermined relative movement of one of said rotary driven elements is effected.

7. In combination with an hydraulically controlled machine tool having relatively movable work and tool supports, and power means for effecting said relative movement at feed and quick traverse rates in opposite directions, of mecha- 75

nism for connecting said power means with the moving support without lost motion comprising a pair of driving helical gears of opposite and unequal tooth angularity rotating as a unit, hydraulic means to exert axially directed pressure to shift said unit, a pair of independent helical gears meshing respectively with the gears of said unit, a lead screw connected with the support, a pair of nut members cooperating with said lead screw and respectively rotated by said independent gears whereby upon longitudinal shifting of said unit said independent gears will be given a limited differential rotational adjustment to eliminate lost motion between the nut members and the lead screw, and means to render said hydraulic means ineffective when said power means is adjusted to yield a quick traverse rate.

8. In a machine tool having relatively movable work and tool supports, and a power operable mechanism for effecting relative movement therebetween at different rates, the combination of means for coupling said mechanism for effecting said relative movement without lost motion therebetween, comprising a lead screw connected to the moving support, a pair of relatively rotatable nut members threaded on the screw and having integral helical gears therewith, intermeshing helical gears of opposite angularity respectively movable as a unit, a fluid operable piston for applying an axial thrust to said helical gear unit to eliminate back lash between said cooperating nut members and the lead screw, and means operable when said power mechanism is adjusted for yielding one of said rates to admit fluid pressure to said piston.

9. In a machine tool having relatively movable work and tool supports and a power operable mechanism for effecting said relative movement at different rates, the combination of means for coupling said mechanism for effecting said movement comprising a lead screw and a pair of cooperating nut members, a first pair of intermeshing helical gears for rotating one of said nut members, a second pair of intermeshing helical gears of opposite angularity to the first pair for rotating the second nut member, the driving members of the gear pairs being connected together with rotation as a unit, means to impart an axial thrust to said unit to effect a differential rotational adjustment of the nut members, said means operating to maintain said adjustment during rotation of the nut members by said power mechanism.

10. In a machine tool having relatively movable work and tool supports and a power operable mechanism for effecting said relative movement at different rates, the combination of means for coupling said mechanism for effecting said

movement comprising a lead screw and a pair of cooperating nut members, a first pair of intermeshing helical gears for rotating one of said nut members, a second pair of intermeshing helical gears of opposite angularity to the first pair for rotating the second nut member, the driving members of the gear pairs being connected together for rotation as a unit, means to impart an axial thrust to said unit to effect a differential rotational adjustment of the nut members, said means operating to maintain said adjustment during rotation of the nut members by said power mechanism, and control devices for rendering said means ineffective during rotation of said nut members at a predetermined one of said rates of said power mechanism.

11. In a machine tool having relatively movable work and tool supports and a power operable mechanism for effecting said relative movement including a feed train and a rapid traverse train, the combination of a final drive mechanism including a lead screw connected to the movable support and a pair of cooperating nut members, one of said nut members having surfaces thereon which lie in a plane which angularly intersects the axis of the nut members, the other nut member having surfaces thereon but of opposite angularity, means movable parallel to the axis of said nut members and simultaneously engageable with said surfaces for effecting a limited differential rotational adjustment of said nut members to eliminate back lash in their connection with the lead screw, and control devices for rendering said means effective when the feed train is connected for movement of the support and for rendering said means ineffective when said rapid traverse train is connected for movement of the support.

12. In a machine tool having relatively movable work and tool supports, and a reversible power mechanism for effecting relative movement therebetween, the combination of means for coupling said mechanism for effecting said movement including a lead screw and a pair of cooperating nut members, said nut members having inclined driving surfaces thereon of opposite angularity, driving members for each nut member having cooperating angular surfaces whereby during one direction of rotation of said nut members a resultant thrust in one direction will be produced in said driving members and upon rotation the thrust resultant will be reversed, hydraulic means for opposing said resultants, and means to change the direction of pressure of said hydraulic means simultaneously with a reversal of said power means.
